UNITED STATES PATENT OFFICE.

JOHN W. GOSSETT, OF RICHMOND, INDIANA.

AUTOMATIC TRAIN STOP.

Application filed October 14, 1924. Serial No. 743,624.

To all whom it may concern:

Be it known that I, JOHN W. GOSSETT, a citizen of the United States, residing at Richmond, in the county of Wayne and State of Indiana, have invented certain new and useful Improvements in Automatic Train Stops; and I do hereby declare the following to be a full, clear, and exact description of the invention, such as will enable others skilled in the art to which it appertains to make and use the same.

The object of this invention is the provision of means for automatically applying the brakes in the event of a car or other unit of a train becoming derailed whereby to check the speed before serious accident may result.

In accordance with the invention the pressure is automatically released from the train pipe of an air brake system to admit of instant and automatic application of the brake in the event of derailment, the safety means being of such construction as to admit of their application to rolling stock and air brake systems without entailing special construction in the installation thereof.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:—

Figure 1 is a detail view showing the application of the invention;

Figure 2 is a side view of the parts illustrated in Figure 1;

Figure 3 is a sectional plan view on the line 3—3 of Figure 1;

Figure 4 is a detail sectional view on the line 4—4 of Figure 3;

Figure 5 is a sectional view on the line 5—5 of Figure 4;

Figure 6 is an enlarged sectional view of the valve mechanism;

Figure 7 is a detail sectional view on the line 7—7 of Figure 6; and

Figure 8 is a fragmental sectional view on the line 8—8 of Figure 6.

Corresponding and like parts are referred to in the following description and design-

nated in the several views of the drawings by like reference characters.

The numeral 10 denotes a portion of the supporting frame of the bottom of a railway car whether designed for freight or passenger service. The numeral 11 designates the track which together with the supporting frame 10 is illustrated to demonstrate the application of the invention.

The usual air line or train pipe of an air brake system is denoted by the numeral 12 and in accordance with the present invention a branch pipe 13 is connected thereto and is provided with a cross pipe 14 and gate valves 15 one at each end of the cross pipe 14. The stems of the gate valves 15 have lateral extensions 16 which project into the path of a trip 17 which is mounted to move vertically.

A transversely disposed bracket 18 is attached to the supporting frame 10 and is strengthened by braces 19. The trips 17 are mounted in the bracket 18 to have a free vertical sliding movement. A guide 20 is connected at its lower end to a cross piece 21 which serves to connect the lower ends of the trips 17 and guides 20. The guides 20 have a limited vertical movement and are freely movable vertically in the bracket 18. It is to be understood that the bracket 18 may be of any preferred construction best adapted for the purpose and location. The cross pieces 21 are conveniently positioned to engage the track rails in the event of derailment thereby opening one or the other of the valves 15 whereby the air pipe is bled or relieved of pressure which results in an automatic application of the brakes in the usual way.

What is claimed is:—

1. Means for automatically applying the brake of an air brake system, the same comprising a branch pipe connected with the train line, a cross pipe attached to the branch pipe and provided at opposite ends with release valves, the stems of which have lateral extensions, vertically slidable trips normally disengaged from said extensions, said extensions being in the path of upward movement of the stems, vertically slidable guides having a limited movement, cross pieces connecting the lower ends of the respective trips and guides and adapted to make contact with a track rail in the event of derailment, and a mounting for the trip and guides.

2. Means for automatically applying the brake of an air brake system comprising a branch pipe connected with the train line, said pipe being transversely disposed with respect to rolling stock, release valves for said pipe mounted on axes extending longitudinally of the rolling stock, said valves having outward extensions, vertically movable trips normally disengaged from said extensions, said extensions being in the path of vertical movement of the trips, whereby upon derailment of rolling stock, the trips will be moved vertically against said extensions to thereby open the valves.
- 10 3. Means for automatically applying the brake of an air brake system comprising a branch pipe connected with the train line,

said pipe being transversely disposed with respect to rolling stock, release valves for said pipe mounted on axes extending longitudinally of the rolling stock, said valves having outward extensions, vertically movable trips normally disengaged from said extensions, said extensions being in the path of vertical movement of the trips, whereby upon derailment of rolling stock, the trips will be moved vertically against said extensions to thereby open the valves, bodies mounting said valves and to which the exhaust pipe directly leads, and supporting means for said body and for the trips, constituting guides for the latter.

In testimony whereof I affix my signature.

JOHN W. GOSSETT.
